UNITED STATES PATENT OFFICE.

PAUL F. E. FEHRMANN, OF SANTA ROSA, CALIFORNIA.

NON-REFILLABLE BOTTLE.

1,145,299.

Specification of Letters Patent.

Patented July 6, 1915.

Application filed June 20, 1914. Serial No. 846,380.

To all whom it may concern:

Be it known that I, PAUL F. E. FEHRMANN, a citizen of the United States, residing at Santa Rosa, in the county of Sonoma and State of California, have invented certain new and useful Improvements in Non-Refillable Bottles, of which the following is a specification.

An object of this invention is the provision of a non-refillable bottle including a bottle neck having a circumferential enlargement provided with grooves permitting the dispensing of the contents of the bottle and a plastic filler molded into the enlargement thereby preventing tampering with the parts of the bottle valve.

Another object is the provision of a non-refillable bottle embodying a novel valve housing in the lower end of which is removably secured the valve seat.

With these and other objects in view, the invention consists in the novel construction, arrangement, and formation of parts as will be hereinafter specifically described, claimed, and illustrated in the accompanying drawing, in which:—

Figure 1 represents a sectional view through the upper portion of a non-refillable bottle constructed in accordance with my invention. Fig. 2 represents a transverse sectional view on the line 2—2 of Fig. 1. Fig. 3 represents a transverse sectional view on the line 3—3 of Fig. 1, and Fig. 4 represents a transverse sectional view on the line 4—4 of Fig. 1. Fig. 5 represents a detail sectional view, partly broken away, of the bottom portion of the bottle.

Referring to the drawing in detail, wherein similar reference numerals designate corresponding parts throughout the several views, the numeral 1 indicates the portion of a bottle of ordinary construction adjacent the neck 2, having an inwardly directed shoulder 3 on its inner face, and a circumferential enlargement 4 adjacent its open end, provided with a series of transversely disposed channels or grooves 5. The open end of the bottle is adapted to be closed by a stopper 6 of the ordinary or any preferred construction.

Intermediate the circumferential enlargement 4 and the shoulder 3, a valve housing 7 is disposed in the neck 2, and provided with a central cavity 8 receiving the

valve 14, preferably of the ball type. The 55 housing 7 is formed with a pair of diametrically opposed and longitudinally extending grooves or channels 9, communicating with the cavity 8, through the opening 11. A hollow annular member 10 is formed 60 integral with the housing 7, snugly fits within the neck 2 of the bottle and is engaged against the shoulder 3. A valve seat 12 is positioned within the annular member 10 and supported on the shoulder 3, and is 65 provided with the usual opening 13 therethrough, adapted to be closed by the valve 20. The valve seat 12 is preferably formed of cork or similar inexpensive material.

A disk 15, preferably formed of cork or 70 a similar fibrous material, is seated within the lower half of the circumferential enlargement 4, and a layer 16 of suitable plastic composition such as cement is laid over the disk 15 and disposed within said enlargement. While the plastic layer of cement 75 is being poured upon the cork disk 15, the grooves or channels 5 are preferably closed by the fingers of a suitable instrument positioned therein, and the fingers are subsequently withdrawn after the plastic material has matured.

In use, the bottle 1 is inverted in the usual manner and the valve 14 moved to the outer end of the cavity 8 by gravity, and the contents of the bottle flows through the openings 13, openings 11, channels 5 and 9. When the bottle is returned to its normal position, as illustrated in Fig. 1, the ball valve 14 is seated against the seat 12, closing 90 the port or opening 13, and preventing the dispensing or evaporation of the contents. When the bottle is not in use the open end thereof is preferably closed by a cork or other stopper 6, to prevent the accumulation 95 of dust in the neck thereof.

What I claim is:—

A non-refillable bottle comprising a bottle neck having a circumferential enlargement adjacent the open end provided with 100 transversely extending channels or grooves, an inwardly directed shoulder on the inner face of said neck, a valve housing seated in said neck between said enlargement and said shoulder and having diametrically opposed 105 and longitudinally extending channels, an annular member formed integral with said housing, and seated on said shoulder, a valve

seat removably seated within said annular member, a fibrous disk positioned upon said valve housing and within said circumferential enlargement, a layer of plastic material positioned upon said disk and permanently seated in said enlargement.

In testimony whereof I affix my signature in presence of two witnesses.

PAUL F. E. FEHRMANN.
